UNITED STATES PATENT OFFICE.

DORA P. GLEASON, OF CINCINNATI, OHIO.

HAIR WAVER.

Application filed September 20, 1924. Serial No. 738,792.

An object of my invention is to provide a hair waver that may be expeditiously applied and removed and that will not catch in the hair when being applied or removed 5 therefrom.

Another object of my invention is to provide a simple and efficient device for the purposes stated.

These and other objects are attained by 10 the means described herein, and disclosed in the accompanying drawings, in which:

Fig. 1 is a perspective view of a hair waver embodying my invention.

Fig. 2 is a view illustrating the method of 15 using a hair waver embodying my invention.

Fig. 3 is an enlarged fragmentary view of a device embodying my invention.

Fig. 4 is a sectional view on line 4—4 of 20 Fig. 3.

The device of my invention comprises a comb 10 and a comb 11, each provided with an outwardly projecting handle 12 and 13 respectively, and with overlapping lugs 14 and 15, that are held in pivotal engagement upon one another by a pin or pivot 16. The handles are each provided with off-set lugs 17 and 18 that engage one another and limit the movement of the combs 10 and 11 25 about the pivot 16, and with abutments 19 and 20, in the nature of comb teeth that engage and limit movement of the combs about the pivot 16 in an opposite direction. The abutments 19 and 20 also serve as a means 30 for grasping or clamping the hair for holding the hair waver in position. A spring 21 is carried by the handles 12 and 13, and is so positioned that it normally and yieldingly retains the abutments 19 and 20 in engagement upon one another.

In practice, a plurality of hair wavers are positioned in the hair in the manner disclosed in Fig. 2, the plurality of wavers together co-operating to develop the hair into 45 a series of waves. By positioning the spring outwardly from the pivot 16, it is possible to dispose the center of weight or stability of the hair waver at or about a line extending longitudinally of the combs, said line 50 being disposed substantially in the backs 22 and 23 of the combs. This tends to somewhat unbalance the comb when applied, and causes the free ends 24 of the comb teeth to raise away from the scalp, thereby attaining a double wave effect in the hair when 55 the wavers are removed. The spring 21

causes the abutting edges 19 and 20 to engage the hair as previously explained, and to hold the combs in position. When applying or removing the hair waver, the combs 60 are moved about the pivot 16 by grasping the handles 12 and 13 between the fingers and moving the handles toward one another against the yielding resistance of the spring 21. The engagement of the lugs 17 and 18 65 limits the extent to which the combs may be moved in this wise, and thereby precludes damage or injury being done to the comb and the spring. The overlapping lugs 14 and 15 provide a substantial mounting of 70 the combs one upon the other, thereby precluding the waver combs from becoming wabbly and serving to retain the abutments 19 and 20, and the lugs 17 and 18 in corresponding planes, thereby precluding mis- 75 alignment of said members.

The abutting teeth 19 and 20 may be placed in a common plane for effecting abutment one upon the other, in any suitable manner, for example, by slightly bending 80 said teeth.

What I claim is:

1. In a hair waver the combination of a pair of combs, each comb being provided with a lug at its end, the lugs overlapping 85 and being hinged one upon the other, each comb having a second lug and an abutment edge, the second mentioned lugs lying in the same plane for engagement upon one another, for limiting movement of the combs 90 about the pivot in one direction, and the abutments likewise lying in a common plane for limiting movement of the combs about the pivot in an opposite direction, and a spring yieldingly retaining the abutments in engagement upon one another. 95

2. In a hair waver the combination of a pair of combs, each comb being provided with a lug at its end, the lugs overlapping 100 and being hinged one upon the other, each comb having a second lug and an abutment edge, the second mentioned lugs lying in the same plane for engagement upon one another, for limiting movement of the combs about the pivot in one direction, and the abutments likewise lying in a common plane 105 for limiting movement of the combs about the pivot in an opposite direction, the abutments being adapted to engage the hair, and a spring for yieldingly retaining the abutments in engagement upon one another, the pivot, the abutments and the spring being 110

substantially aligned, the pivot being intermediate the spring and the abutments.

3. In a hair waver, the combination of a pair of combs substantially identical in structure, each comb having a lug adapted to overlap a similar lug on the other comb, a pivot extending through the lugs and pivotally securing the combs upon one another at their ends, whereby the combs extend substantially in opposite directions away from the pivot, each comb having an abutment upon one of its teeth for engagement upon the similar abutment of the other comb, and a spring disposed outwardly of the back of the combs engaging each of the combs and yieldingly retaining the abutments upon one another.

4. In a hair waver, the combination of a pair of combs substantially identical in structure, each comb having a lug adapted to overlap a similar lug on the other comb, a pivot extending through the lugs and pivotally securing the combs upon one another at their ends, whereby the combs extend substantially in opposite directions away from the pivot, each comb having an abutment upon one of its teeth for engagement upon the similar abutment of the other comb, and a spring disposed outwardly of the back of the combs engaging each of the combs and yieldingly retaining the abutments upon one another, the abutments, the pivot and the spring being substantially aligned, the pivot being intermediate the spring and the abutments.

5. In a hair waver, the combination of a pair of combs substantially identical in structure, each comb having a lug adapted to overlap a similar lug on the other comb, a pivot extending through the lugs and pivotally securing the combs upon one another at their ends, whereby the combs extend substantially in opposite directions away from the pivot, each comb having an abutment upon one of its teeth for engagement upon the similar abutment of the other comb, and

a spring disposed outwardly of the back of the combs engaging each of the combs and yieldingly retaining the abutments upon one another, the abutments, the pivot and the spring being substantially aligned, the pivot being intermediate the spring and the abutments, each comb being provided with a second lug for engagement upon the similar lug on the other comb and limiting the movement of the comb in one direction about the pivot, the abutments on the combs being adapted to limit the movement of the combs in an opposite direction about the pivot.

6. In a hair waver, the combination of a pair of combs substantially identical in structure, each comb having a lug adapted to overlap a similar lug on the other comb, a pivot extending through the lugs and pivotally securing the combs upon one another at their ends, whereby the combs extend substantially in opposite directions away from the pivot, each comb having an abutment upon one of its teeth for engagement upon the similar abutment of the other comb, and a spring disposed outwardly of the back of the combs engaging each of the combs and yieldingly retaining the abutments upon one another, the abutments, the pivot and the spring being substantially aligned, the pivot being intermediate the spring and the abutments, each comb being provided with a second lug for engagement upon the similar lug on the other comb and limiting the movement of the comb in one direction about the pivot, the abutments on the combs being adapted to limit the movement of the combs in an opposite direction about the pivot.

7. In a hair waver, the combination of a pair of combs substantially identical in structure, each comb having a lug adapted to overlap a similar lug on the other comb, a pivot extending through the lugs and pivotally securing the combs upon one another at their ends, whereby the combs extend substantially in opposite directions away from the pivot, each comb having an abutment upon one of its teeth for engagement upon the similar abutment of the other comb, and a handle carried by each comb, disposed adjacent the first mentioned lugs on the comb, and extending from the backs diametrically opposite to the teeth of the combs.

In testimony whereof, I have hereunto subscribed my name this 17th day of September, 1924.

DORA P. GLEASON.
